(57) **CLAIM**

The ornamental design for a workstation trolley as shown and described.

DESCRIPTION

FIG. 1 is a perspective view of a workstation trolley showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged detail view of the workstation trolley according to Circular Area 8 circumscribed within FIG. 2; FIG. 9 is an enlarged detail view of the workstation trolley according to Circular Area 9 circumscribed within FIG. 4; and,

FIG. 10 is an enlarged detail view of the workstation trolley according to Circular Area 10 circumscribed within FIG. 5. The broken lines in the drawings depict portions of the workstation trolley that form no part of the claimed design.

1 Claim, 10 Drawing Sheets
